TREATMENT OF PETROLEUM OILS

Thomas Oliver Edwards, Jr., and Oscar Larson,
Associated, Calif., assignors to Tide Water
Associated Oil Company, San Francisco, Calif.,
a corporation of Delaware

Application May 9, 1938, Serial No. 206,776

15 Claims.

(Cl. 196—35)

This invention relates to the distillation of petroleum and the treatment of the same with alkalies such as caustic soda, and has for its principal purpose the recovery of various oil fractions of suitable purity for commercial use.

A second purpose is the continuous distillation of lubricating oil fractions with only a small fraction rejected as bottoms.

A third purpose is the continuous distillation of lubricating oil fractions in the presence of alkali whereby the various fractions are recovered free of contaminants.

A fourth purpose is to provide a method for the continuous distillation of lubricating stocks in the presence of alkali whereby the service factor of the still is increased and the repair cost reduced.

Other purposes will be apparent from the following description.

In the distillation of lubricating oils it is common practice to conduct the distillation in the presence of caustic soda or other alkali whereby acidic bodies, such as naphthenic acids and phenols, are retained in the bottoms as soaps or salts of the alkali used. In continuous distillation the alkali is normally injected into the oil stream to be distilled. The presence of this alkali has a corrosive action on the heating tubes and other highly heated parts of the apparatus. Deposits of solid or semi-solid alkali also form in the heating tubes, resulting in decreased heat transfer, overheated tubes, decreased time on stream, and increased repair costs. It is therefore a purpose of this invention to provide a means for removing the major portion of the alkali from the oil before the oil enters the tube still.

In modern vacuum fractionating towers, particularly when steam is injected for stripping purposes, there is a tendency for the soaps formed to hydrolyze, liberating free acidic bodies which are carried up with the vapors to the lower plates of the tower sometimes along with portions of the alkali. To obviate this contamination it has generally been necessary to either inject large excesses of alkali to reduce the hydrolyzation or to maintain a high rate of refluxing on the lower plates of the tower. The injection of large amounts of alkali results in an increase in the corrosion difficulties encountered as well as an increase in the amount of alkali entrained by the vapors and carried upward in the tower. The maintenance of a high reflux on the lower plates of the tower results in a large amount of valuable heavy lubricating stock being rejected with the bottoms from the distillation. Attempts have

been made to recycle these bottoms, or a portion thereof, with the fresh charge to reduce the amount of oil rejected. Such practice almost invariably results in increased corrosion due to the entrained alkali and in poorer quality products due to the asphaltic matter in the bottoms.

It has been found that acidic bodies which are formed by the hydrolysis of the soaps or by decomposition of a small portion of the oil in the heating tubes may be accumulated in a heavy fraction on one of the lower plates of the fractionating zone of the tower, which fraction may then be returned to the still together with the fresh charge. Any alkali entrained by the vapors is also accumulated in this heavy fraction and is thereby removed from the finished distillates.

The single sheet of drawings illustrates in Fig. 1 a preferred form of fractionating column in vertical section which is diagrammatically connected with other apparatus to show one form of utilizing the invention and Fig. 2 shows a mixer or agitator for the chemical treatment of the oil withdrawn from pipe 28.

Lubricating oil stock to be distilled and containing only a small percentage of asphaltic matter (such as, for example, once distilled lubricating distillate, lubricating distillate from crude oils low in asphalt, or distillates which have been previously treated by physical or chemical means) is forced from line 1 by pump 2 through heating coil 3, which may be advantageously a heat exchanger, where it is heated to a temperature suitable for alkali treatment. A temperature from about 200° to 500° F. has been found suitable for such treatment. To the oil leaving coil 3 through pipe 4 there is supplied a water solution or suspension of alkali from pipe 4a. Such alkali may be NaOH, KOH, Ca(OH)₂, MgOH, CaO, or any alkali found suitable for combining with the acidic compounds of the oil, although those alkalis forming the most stable and oil insoluble soaps are more desirable. For this reason the alkali metal hydroxides and carbonates are especially preferred but generally the hydroxides and carbonates of both the alkali metals and alkaline earth metals can be used. Sufficient alkali is used to combine with the acidic compounds present in the oil and the amount varies from a very small quantity, such as 0.01 pound, up to 5 pounds per barrel of oil, depending on the character of the oil to be treated.

From pipe 4 the oil and alkali pass into settling chamber 5, maintained under sufficient pressure to hold the water in liquid form. From the settling chamber the solution of soaps and excess

alkali is drawn off through valve 6 and pipe 1. Settling chamber 5 may be of any design suitable for separation of the alkali solution from the oil under the pressure developed by the treating temperature. It may contain Raschig rings, baffles, or the like to assist in the settling of the alkali sludge. Mechanical separators such as centrifuges or filters may be used, if desired, to facilitate the settling of the sludge. If, however, it is desired to further heat or distill the oil with the alkali present, the water may be flashed off from chamber 5 through valve 8.

When the oil to be distilled has been previously carefully treated with sulphuric acid or solvent extraction, the alkali requirement generally does not exceed 0.2 to 0.3 pound of caustic soda (or its equivalent of other alkali) per barrel of oil. In such a case it may be well to distill the oil in the presence of this small amount of alkali in order to neutralize acidic materials which may be formed by decomposition of the oil during the subsequent heating.

The oil after treatment with the alkali passes from the settling chamber 5, through pipe 9, to the main heating coil 10, situated in furnace 11 and heated by burner 12, where it is heated to the desired temperature for distillation, suitable temperatures being well known to those familiar with the art of lubricating oil distillation.

From the heating coil 10 the heated oil passes through transfer line 13 and control valve 13a to tower 14, which is preferably maintained under a substantial vacuum by means of a vacuum pump or other suitable means not shown. Steam, or other gas, if desired, enters at the bottom of tower 14 through pipe 15 and distributing ring 16, and assists in the vaporization and fractionation of the oil according to well known methods. Vacuum tower 14 contains a plurality of bubble plates or baffles 17 of conventional design through which the vapor and steam pass and on which a level of reflux oil is maintained to wash the vapors. A similar set of bubble plates or baffles 18 is preferably placed below the inlet of pipe 13 and above the steam inlet 16 to act as a stripping section. The steam inlet 16 may be replaced or supplemented by a heating coil or other source of additional heat if desired.

On one side of each of the bubble plates 17 are situated weir boxes 19 so constructed as to maintain a desired level of liquid on each plate. The excess oil on each plate enters the weir boxes and is returned to the opposite side of the next lower plate through pipes 20 and valves 21 which are preferably controlled from the outside of the tower. Excess oil not required to wet the next lower plate may be withdrawn through pipes 22 by means of suitable pumps or suction apparatus 23.

The oil layer on the lowest plate of the fractionating zone serves to wash the ascending vapors and free them from entrained alkali, soaps, and asphaltic matter. It has been found that the oil accumulating on this lowest plate and entering its weir box 19 contains the greater portion of the free acids formed by the hydrolysis of the soaps. In conventional practice this oil is returned to the stripping section of the tower and passes out with the bottoms from the distillation through pipe 24 and thus a valuable lubricating fraction is lost as bottoms. According to this invention, however, the lowest plate of the fractionating zone has no down pipe and the oil containing the impurities is withdrawn from the weir box 19 of this plate through pipe 26.

The withdrawn oil is then cyclically returned to the process through valve 21 and pipe 28 and is mixed with fresh oil entering through pipe 1. In this manner the amount of bottoms formed in the distillation, and removed through pipe 24, is reduced to a very small percentage, such as 0.2% to 3.0%, and generally below 5% to 10%, of the oil distilled. The remaining oil is recovered as valuable distillate from the other plates of the tower.

The acidic bodies concentrated in the recycle oil from the lowest plate of the fractionating section are removed by the alkali treatment along with the acidic bodies from the fresh oil charge. However, at times, and especially when soaps are not withdrawn from settling chamber 5 through pipe 1, there is built up in the system a gradually increasing amount of acidic compounds. In such cases a portion of the recycle oil passing through pipe 26 can be removed from the system through valved line 29. This removed oil may be discarded or used for lubricating equipment where the presence of acidic bodies is unimportant or even advantageous. However, it has been found advantageous to chemically treat this withdrawn oil and return it to the system through valved line 30.

Regardless of whether or not soaps are withdrawn from settling chamber 5 (through pipe 1), decomposition products resulting from the heating in coil 10 accumulate in the oil and it has been found desirable to close valve 21 and withdraw the entire stream from the bottom plate of the fractionating section through line 29. This withdrawn oil is then treated with alkali, or preferably with acid, or with acid and then with alkali, and returned through line 30. Other treatments, for example with clay, may be used instead of, or to supplement, the acid or alkali treatment to remove the acidic and decomposition products. To enhance the treating of this so withdrawn oil, which is highly viscous, and to avoid excessive emulsification during its treatment it has been found advantageous to decrease its viscosity by blending therewith a low viscosity oil. Such low viscosity oil may conveniently be a light fraction taken from one of the upper plates of the tower, or a low viscosity raw, untreated distillate may be used. In the latter case when a raw distillate is mixed with the viscous recycle oil, it is obviously necessary to treat the mixture by whatever chemical treatment that is required by the raw, light oil.

The described chemical or clay treatments may be carried on in accordance with any well known or conventional process or apparatus such as diagrammatically shown in Fig. 2, either in batch or continuous treatments, but such specific treatments form no part of the present invention and can be generally illustrated as providing that the stream of contaminated oil drawn through pipe 29 may be passed, in whole or in part, into any well known agitator or mixing chamber 31. If only a part is treated, the remainder may be withdrawn through pipe 32.

Acid may be introduced into the oil in agitator 31 through pipe 33 and, after treatment therein for the desired period, the acid sludge can be settled and removed through pipe 34 and the purified oil returned through pipe 30. In similar manner alkali or clay can be introduced through pipe 35 for the described purposes.

When operating in the above described manner it has been found that the oil fractions obtained from various fractionating plates, except

the lowest, are of satisfactory quality for commercial use and ordinarily require no further treatment, while the length of time in which the still may normally operate without mechanical failure has been increased over six-fold. Following are examples of color and color stability of various fractions obtained when operating the process on naphthenic base lubricating stock which has been previously distilled and acid treated:

Viscosity of fraction S. U. at 100° F.	Color 6 th Lovibond cell	Color after 6 hrs. heating at 240° F. 6 th Lovibond cell
100	10	20
500	50	75
1,800	90	130
4,000	250	300

The invention comprises in its use the following modes of operation:

(1) When an oil either contains acidic compounds, such as naphthenic acids, or has been so treated with acids, such as sulphuric acid, or with liquid SO₂ that it contains residual acidity, then sufficient alkaline solution is added through pipe 4a to neutralize such acidic compounds and to remove the neutralization products in settling chamber 5.

(2) When an oil contains no acidic compounds, as above stated, there is, however, a decided tendency for acidic compounds to be formed in heating coil 10 together with decomposition products in which an alkaline solution in relatively small amounts will be introduced through pipe 4a sufficient to neutralize such formed acidic compounds.

This small amount of alkali need not exceed 0.2 to 0.3 pound of caustic soda, or other equivalent alkali, per barrel of oil and is such as to have a negligible effect on corrosion or incrustation of the heating tubes while fully effective in neutralizing acidic compounds formed in such tubes.

In either mode of operation, it will be understood that any alkali carried into heating coil 10 is substantially anhydrous alkali, and the removal of soaps is primarily accomplished in liquid phase through pipe 7 leaving only a minimum quantity of anhydrous alkali to pass through coil 10 and in this event formed acidic compounds will either be removed by recycling through pipe 28 or by chemical treatment prior to such recycling.

Alternatively, when required, when water is flashed off through valve 8, there will generally be no liquid withdrawal through pipe 7 and a relatively large amount of anhydrous alkali passed through coil 10 which will further neutralize any acidic compounds formed in coil 10.

The temperature to which the oil is heated in coil 10 is generally sufficient for distillation purposes only and, for vacuum distillation of lubricating oils, is not such as would cause substantial decomposition or cracking, but any decomposition is incidental and unavoidable.

At the same time, while describing the invention in a preferred form, it is intended only to be limited in its application as set forth in the appended claims.

We claim as our invention:

1. The method of treating oil which comprises, contacting hydrocarbon oil containing acidic compounds with an alkali in the presence of water at a temperature between 200° and 500° F.,

fractionally distilling the contacted oil to remove not less than about 97% as distillates, and recovering from said distillation a relatively low boiling fraction substantially free from acidic bodies, an intermediate fraction containing acidic bodies, and a bottoms fraction between about 0.2% and 3.0% of the original charge.

2. The method of treating oil which comprises, contacting hydrocarbon oil containing acidic compounds with an alkali in the presence of water at a temperature between 200° and 500° F., under pressure sufficient to prevent substantial vaporization of the water, separating the resulting aqueous layer, fractionally distilling the contacted oil to remove not less than about 97% as distillates, and recovering from said distillation a relatively low boiling fraction substantially free from acidic bodies, an intermediate fraction containing acidic bodies, and a bottoms fraction between about 0.2% and 3.0% of the original charge.

3. The method of treating oil which comprises, contacting hydrocarbon oil containing acidic compounds with an alkali in the presence of water at a temperature between 200° and 500° F., flashing off the water from the mixture of oil and alkali, fractionally distilling the contacted oil to remove not less than about 97% as distillates, and recovering from said distillation a relatively low boiling fraction substantially free from acidic bodies, an intermediate fraction containing acidic bodies, and a bottoms fraction between about 0.2% and 3.0% of the original charge.

4. The method of treating oil which comprises, contacting a hydrocarbon oil low in asphaltic content and containing acidic compounds with an alkali metal hydroxide in the presence of water at a temperature between 200° and 500° F., fractionally distilling the contacted oil to remove not less than about 97% as distillates, and recovering from said distillation a relatively low boiling fraction substantially free from acidic bodies, an intermediate fraction containing acidic bodies, and a bottoms fraction between about 0.2% and 3.0% of the original charge.

5. The method of treating oil which comprises, contacting a lubricating hydrocarbon oil low in asphaltic content and containing acidic compounds with an alkali in the presence of water at a temperature between 200° and 500° F., fractionally distilling the contacted oil under vacuum to remove not less than about 97% as distillates, recovering from said distillation a relatively low boiling fraction substantially free from acidic bodies, an intermediate fraction containing acidic bodies, and a bottoms fraction between about 0.2% and 3.0% of the original charge.

6. The method of treating oil which comprises, contacting a lubricating hydrocarbon oil low in asphaltic content and containing acidic compounds with an alkali in the presence of water at a temperature between 200° and 500° F., fractionally distilling the contacted oil under vacuum to remove not less than about 97% as distillates, recovering from said distillation a relatively low boiling fraction substantially free from acidic bodies, an intermediate fraction containing acidic bodies, and a bottoms fraction between about 0.2% and 3.0% of the original charge, and recycling at least a portion of said intermediate fraction to the alkali contacting step.

7. The method of treating oil which com-

prises, contacting hydrocarbon oil containing acidic compounds with an alkali in the presence of water at a temperature between 200° and 500° F., fractionally distilling the contacted oil, recovering from said distillation a relatively low boiling fraction substantially free from acidic bodies, an intermediate fraction containing acidic bodies, and a bottoms fraction between about 0.2% and 3.0% of the original charge, treating said intermediate fraction to remove acidic and decomposition bodies, and returning such treated fraction to the alkali contacting step.

8. The method of treating oil which comprises, contacting hydrocarbon oil containing acidic compounds with an alkali in the presence of water at a temperature between 200° and 500° F., fractionally distilling the contacted oil, recovering from said distillation a relatively low boiling fraction substantially free from acidic bodies, an intermediate fraction containing acidic bodies, and a bottoms fraction between about 0.2% and 3.0% of the original charge, treating said intermediate fraction with sulfuric acid, and returning such treated fraction with the fresh charge to the alkali contacting step.

9. The method of treating oil which comprises, contacting lubricating hydrocarbon oil containing acidic compounds with an alkali in the presence of water at a temperature between 200° and 500° F., fractionally distilling the contacted oil, recovering from said distillation a relatively low boiling fraction substantially free from acidic bodies, an intermediate fraction containing acidic bodies, and a bottoms fraction between about 0.2% and 3.0% of the original charge, reducing the viscosity of said intermediate fraction by blending therewith a low viscosity hydrocarbon oil, treating the resulting blend with sulfuric acid, and introducing the treated blend with the fresh charge to the alkali contacting step.

10. A process of treating oil which comprises, flowing a continuous stream of hydrocarbon oil containing acidic compounds and alkali through a heating stage under superatmospheric pressure, expanding the mixture into a fractionating zone of lower pressure wherein the major portion of said oil is vaporized, fractionally condensing said vaporized oil in said zone, and separately withdrawing uncontaminated condensed fractions and contaminated condensed fractions to leave a bottoms fraction between 0.2% and 3% of the original charge.

11. A process of treating oil which comprises, flowing a continuous stream of hydrocarbon oil containing acidic compounds and an aqueous alkaline solution through a heating stage under superatmospheric pressure, separating at least a portion of said solution from said mixture, ex-

panding the mixture into a fractionating zone of lower pressure wherein the major portion of said oil is vaporized, fractionally condensing said vaporized oil in said zone, and separately withdrawing uncontaminated condensed fractions and contaminated condensed fractions to leave a bottoms fraction between 0.2% and 3% of the original charge.

12. In a process of refining lubricating oil containing acidic compounds in which the oil is heated in the presence of an alkaline material and then fractionated to obtain a series of distillates varying in gravity, the combination of steps which comprises, withdrawing the heaviest distillate of said series from the fractionating step, treating said distillate to remove acidic and decomposition products resulting from said heating, and returning at least a portion of such treated distillate to said heating step.

13. In a process of refining lubricating oil containing acidic compounds in which the oil is heated in the presence of an alkaline material and then fractionated to obtain a series of distillates varying in gravity, the combination of steps which comprises, withdrawing the heaviest distillate of said series from the fractionating step, mixing a lower viscosity oil with said distillate, treating the mixture to remove acidic and decomposition products resulting from said heating, and returning at least a portion of such treated distillate to said heating step.

14. A process of refining oil which comprises: mixing hydrocarbon oil heated from about 200° to 500° F. with an aqueous alkaline solution, removing the water of solution, further heating the oil containing substantially anhydrous alkali to a temperature at which not less than 90% of the oil will vaporize at a reduced pressure, expanding the heated oil to cause such vaporization, withdrawing the unvaporized oil, fractionating the thus vaporized oil, withdrawing the heaviest fraction thus obtained, and returning the said heaviest fraction to the said mixing step.

15. A process of refining oil which comprises: mixing hydrocarbon oil heated from about 200° to 500° F. with an aqueous alkaline solution, removing the water of solution, further heating the oil containing substantially anhydrous alkali to a temperature at which not less than 90% of the oil will vaporize at a reduced pressure, expanding the heated oil to cause such vaporization, withdrawing the unvaporized oil, fractionating the thus vaporized oil, withdrawing the heaviest fraction thus obtained and chemically treating the same to remove decomposition products and returning the said heaviest fraction to the said mixing step.
